UNITED STATES PATENT OFFICE

ALBERT E. F. MOONE, OF CHICAGO, ILLINOIS, ASSIGNOR TO THE LEHON COMPANY, OF CHICAGO, ILLINOIS, A CORPORATION OF ILLINOIS

DESIGN FOR ROOFING

Application filed April 23, 1930. Serial No. 35,359. Term of patent 14 years.

To all whom it may concern:

Be it known that I, ALBERT E. F. MOONE, a citizen of the United States, residing at Chicago, in the county of Cook and State of Illinois, have invented a new, original, and ornamental Design for Roofing, of which the following is a specification, reference being had to the accompanying drawing, forming a part thereof.

The figure is a plan view of several strips of roofing embodying my design superimposed in overlapping relation.

I claim:

The ornamental design for roofing, substantially as shown.

ALBERT E. F. MOONE.
